UNITED STATES PATENT OFFICE.

ERVIN R. ELLIS, OF WASHINGTON, DISTRICT OF COLUMBIA, ASSIGNOR OF THREE-FIFTHS TO GOLDBERG BROTHERS COMPANY, INC., OF RICHMOND, VIRGINIA.

DESIGN FOR A DISPLAY STAND.

Application filed February 27, 1928. Serial No. 25,602. Term of patent 3½ years.

To all whom it may concern:

Be it known that I, ERVIN R. ELLIS, a citizen of the United States of America, residing at Washington, in the District of Columbia, have invented a new, original, and ornamental Design for Display Stand, of which the following is a specification, reference being had to the accompanying drawing, forming part thereof.

Figure 1 is a perspective view of the display stand; and,

Figure 2 is a top plan view of the same.

I claim:

The ornamental design for a display stand, as shown.

ERVIN R. ELLIS.
